DEVICE FOR PRODUCING THE HELICOIDAL DEFORMATION OF THE PLANES OF AEROPLANES.

1,006,106

Specification of Letters Patent. Patented Oct. 17, 1911.

Application filed June 24, 1910. Serial No. 568,685.

To all whom it may concern:

Be it known that I, LÉON MARIE JOSEPH CLÉMENT LEVAVASSEUR, citizen of the Republic of France, residing at Puteaux, 5 Seine, France, have invented certain new and useful Improvements in Devices for Producing the Helicoidal Deformation of the Planes of Aeroplanes, of which the following is a specification.

10 This invention relates to a device by means of which the helicoidal deformation of the planes of aeroplanes can be effected so as to avoid turning over under the action of side winds.

15 A construction of the device according to this invention is illustrated by way of example in the accompanying drawing which shows it diagrammatically in perspective.

The planes a a' arranged above the body 20 b are each constructed of canvas stretched on a frame formed by a fixed rod c and a rod d pivoted at e , the two rods being connected by cross-bars f . The two movable rods d are connected respectively above and below 25 the planes by flexible cables g and h secured at m and n to the said rods. The cable g passes over a pulley i arranged at the end of the upper vertical arm j . The cable h passes over a pulley k mounted at the end of 30 the bottom vertical arm l .

An operating or controlling mechanism is provided, said mechanism being constituted in the construction illustrated by a hand wheel o , a pulley q keyed to the spindle 35 of the hand wheel o over which and over the guide rollers r passes the cable p , and a lever s secured to the pulley k , and having the cable p secured to its ends, so that the operator can rotate the pulley k in one or the 40 other direction. Assuming that the movement imparted to the pulley k is that shown by the arrow 1, the cable h will be moved in the direction of the arrows 2, while the cable or chain g will be moved in the direction of the arrows 3. The result obtained 45 will be an angular movement of the pivoted rod d of the right plane above its original position, and an angular movement to the same extent of the pivoted rod d of the left

50 plane below its original position. In that way, as shown in dotted lines, there will be obtained a certain warping or helicoidal

deformation of the planes a a' which will be zero at the pivot point e and increase gradually toward the end of the rods d where the 55 deformation in question will be the maximum. By giving to the pulley k a movement of rotation in a direction opposite to the arrow 1, the deformation of the planes will be in the opposite direction, that is to 60 say, the planes will be warped in the following manner: the right wing above, and the left wing below, so that by suitable manipulation the action of lateral winds will be counteracted, whether they act on one or 65 on the other side of the apparatus.

Claim:

1. In a flying-machine, a pair of wings extending transverse to the line of flight, a rigid stay to which the front edges of said 70 wings are secured, a pair of pivoted stays to which the rear edges of said wings are secured, each of such stays being attached to the corresponding wing substantially throughout the length of the same, said 75 latter stays being pivoted at a common point, and mechanism for simultaneously moving said latter stays about such pivotal point to raise one and lower the other, whereby a helicoidal deformation of the 80 wings is produced.

2. In a flying-machine, a pair of wings extending transverse to the line of flight, each of said wings normally lying in a plane, said planes intersecting in a line parallel with the axis of flight, a common rigid stay to which the front edges of both of said wings are secured, a pair of pivoted stays to which the rear edges of said wings are secured, said latter stays being pivoted at 85 a fixed common point on the line of intersection of the planes, and means for simultaneously moving said last mentioned stays about such fixed pivot to raise one and lower the other, whereby a helicoidal deformation 90 of said wings is produced.

In testimony whereof I affix my signature in presence of two witnesses.

LÉON MARIE JOSEPH
CLÉMENT LEVAVASSEUR.
